UNITED STATES PATENT OFFICE

JAMES L. BREESE, JR., OF CHICAGO, ILLINOIS, ASSIGNOR TO OIL DEVICES CORPORATION, OF CHICAGO, ILLINOIS, A CORPORATION OF ILLINOIS

CLOSURE FOR USE WITH BURNER UNITS

Original application filed November 17, 1927, Serial No. 233,787. Divided and this application filed March 14, 1928. Serial No. 261,465.

My invention relates to a closure for doors for furnaces, boilers and the like, which is particularly useful for use with hydrocarbon or liquid or gaseous fuel burning units. 5 One object of my invention is to provide means for sealing off the air in the ash pit door when a heating unit of the type herein described and shown is inserted through said door. Another object is the provision of 10 means for applying a heating unit of the type described to a furnace or the like without the necessity of bricking up or otherwise permanently modifying the furnace or the door. Other objects will appear from 15 time to time in the course of the specification and claims.

The present application is a division of my copending application No. 233,787, filed on November 17, 1927, for hydrocarbon burner.

20 I illustrate the invention more or less diagrammatically in the accompanying drawings, wherein—

Figure 1 is a vertical section through a furnace and heating unit with the door in 25 position;

Figure 2 is a section on the line 2—2 of Figure 1, showing the door in position; and

Figure 3 is a perspective view of the furnace with the heating unit about to be inserted and the door removed.

Like parts are indicated by like symbols throughout the specification and drawings.

A generally indicates a heater of a well known type having the usual supporting legs 35 A¹, a flue escape pipe A² and a fire box door A³.

B indicates a fuel supply and heater unit having a combustion member B¹. The latter includes a bottom portion B² resting upon the 40 bottom of the ash pit A⁴ of the heater A, and provided with the upwardly projecting generally cylindrical wall B³ in communication with which is the longitudinal air inlet passage B⁴, which is braced by the member B⁵ to 45 the wall B³. Said wall may be provided with

indentations B⁶ for clearing the lugs A⁵ or other projections inside the ash pit opening.

Seated upon the upper edge of said wall is a mixing chamber having the bottom portion C which may be concave as shown and the upwardly projecting cylindrical side wall C¹, which may be made of two parts C² C³ secured together by the crimp C⁴. C⁵ are a plurality of large and small apertures 50 penetrating the upper part C³ of the wall, 55 permitting air to enter the mixing chamber. Externally projecting from the wall C¹ is a circular flange C⁶ with a downwardly projecting ring C⁷ adapted to be seated upon the upper edge of the drum B⁸. C⁸ is a conic 60 shaped split ring positioned in the circular depression or groove C⁹ in the wall C¹.

D generally indicates a fuel passage extending from the fuel tank base member D¹ with its tank D² and float D³ to the elbow D⁴ 65 through which the fuel is supplied to the interior of the shell C². D⁵ indicates any suitable valve for controlling the flow of the fuel and D⁶ adjustable supports for the fuel tank, with the members D⁷ screwthreaded 70 thereto and the locking screws D⁸.

It will be realized that whereas I have described a practical and operative heating unit, my ash pit door closure may be employed with a wide variety of heating units, 75 or may even have uses entirely dissociated with any such heating unit.

Referring to the drawings it will be seen that the usual ash pit door of the heater A has been removed and has been replaced by 80 the closure plate H cut away as at H¹ to conform to the shape of the laterally projecting air passage B⁴. H² is a locking member, hinged as at H³ to the usual pin H⁴ provided 85 for the ash pit door. H⁵, H⁶ are spring members mounted on the member H² adapted for frictional engagement with the plate H, pressure being applied by means of the screwthreaded stud H⁶ mounted in the heater A and penetrating the locking member H² and 90

the wing nut H^7 . The hinged means are movable independently of the plate and the springs are preferably, but not necessarily, unconnected with the plate except so far as they are thrust against it by the action of the hinged locking member or cross piece H^2 .

It is understood that the usual grate associated with the heater A may preferably be removed as shown, leaving free access to the combustion chamber A^7 .

It will be realized that whereas I have shown a practical and operative device, nevertheless many changes might be made in size, shape, number and distribution of parts without departing from the spirit of my invention. I therefore wish my drawings and description to be taken as in a broad sense illustrative or diagrammatic rather than as limiting me to my specific description and showing. The use and operation of my invention are as follows:

The heater unit herein shown may be applied to any heater, for example a coal burning heater, by merely lifting off the ash pit door and removing the grates and inserting the mixing chamber. This ready conversion of a coal burning plant to an oil burning plant is of great importance.

In order to prevent the inflow of air through the grate door, the grate door being removed, I provide the structure shown in detail in Figures 2 and 3 which includes the plate H , cut away as at H^1 to conform to the air passage B^4 , upon which it may rest. In order to hold it against the edges of the grate door I provide vertical spring arms H^5 which are secured to the transverse strip H^2 , one end of which is hinged to the normal pivot pin H^4 of the ash pit door, whereas the other is secured at the opposite side of the door, for example by the screwthreaded stud H^6 and the wing nut H^7 . The result is a constant yielding pressure against the closure member H , which keeps it tightly sealed in place the pressure being applied particularly to the four corners of the plate.

I claim:

1. A closure for the door opening to the ash pit of a furnace comprising a free closure plate shaped to permit the passage of a fuel conduit and closely fitting the same and adapted to be applied over the said opening, and hinged means arranged to yieldingly hold the closure plate in place, movable independently of the plate and arranged to be swung into holding engagement therewith after the same has been applied.

2. A closure for the door opening to the ash pit of a furnace adapted to replace the usual ash pit door, comprising a free plate, conforming generally to the said opening and constructed to permit the passage of a fuel supply conduit into the ash pit and to fit closely over the same, a transverse bar hinged at one end to one side of the opening and

extending across the central portion of the closure plate when the latter is in place, leaf springs secured at their central portions to the cross bar near its ends, the free ends of such springs being arranged to bear against the closure plate at its corner portions, and means for securing the free end of the cross bar with the springs in holding engagement with the closure plate.

Signed at Chicago county of Cook and State of Illinois, this 8th day of March, 1928.

JAMES L. BREESE, JR.
